UNITED STATES PATENT OFFICE

CARL G. NAYLOR, OF CHICAGO, ILLINOIS, ASSIGNOR TO NAYLOR-ROBERTSON COMPANY, A CORPORATION OF DELAWARE.

EXPANSIBLE MANDREL.

Application filed January 14, 1921. Serial No. 437,231.

To all whom it may concern:

Be it known that I, CARL G. NAYLOR, a citizen of the United States, residing at Chicago, in the county of Cook and State of Illinois, have invented certain new and useful Improvements in Expansible Mandrels, of which the following is a specification.

The invention relates to improvements in expansible mandrels.

10 One of the objects of the invention is to provide a new and improved expansible mandrel.

Another object is to provide a sectional mandrel, one or more of which sections may 15 be expanded to varying predetermined extent.

Another object is to provide a mandrel especially adapted for use in a machine for making spiral pipe of strips of sheet metal 20 such as fully described in my Patent No. 1,288,134, granted to me December 17, 1918.

Other, further and more specific objects 25 of the invention will become readily apparent, to persons skilled in the art, from a consideration of the following description, when taken in conjunction with the drawings, wherein:

Fig. 1 shows a diametric axial section of one end of the mandrel having a plurality 30 of removable nonexpansible or rigid sections.

Fig. 2 is a similar view showing a continuation of the mandrel and one expansible section with means for expanding it.

35 Fig. 3 is an end elevation of a terminal flange secured to the shaft to provide an abutment and looking from the left towards Fig. 1.

Fig. 4 is a transverse section taken on 40 line 4—4 of Fig. 2.

Fig. 5 is a section of the split ring for insertion in a groove in the mandrel shaft and an unbroken ring to hold it in place to limit the axial movement of the members on the 45 shaft.

Fig. 6 is an enlarged transverse section taken on line 6—6 of Fig. 2.

Fig. 7 is an enlarged transverse section taken on line 7—7 of Fig. 2.

50 Fig. 8 is an elevation of a fragmental end of the expansible section and means for expanding it, showing in sections the position of the parts when the mandrel is expanded.

Fig. 9 is a similar view showing the position of the parts when the mandrel is diametrically contracted.

Fig. 10 is an enlarged axial section of part of one end of the expansible mandrel.

Fig. 11 is an enlarged sectional view of part of one end of the axially movable sleeve 60 or toggle head used for expanding the expansible section of the mandrel.

In all the views the same reference characters are employed to indicate similar parts.

A shaft 15 may be rotated by any suitable 65 means and, on this shaft, the mandrel sections are to be mounted. For convenience the mandrel is preferably divided into a series of sections 16 of which there may be any desired number according to the length 70 of mandrel required.

An abutment flange 17, which may be a member of a shaft coupling, is properly secured to the shaft 15, in any suitable manner, the flange 18 of which is perforated, as at 19, 75 to receive a plurality of pins 20 that project from the thrust washer 21. Around each of the pins is coiled an open helical spring 22 to permit some axial movement of the composite mandrel on the shaft 15 at the 80 time when the mandrel is being expanded and contracted.

Mounted on the shaft 15 is a series of spacing sleeves 23 alternately with a series of bushings 24. The sections 16 to 16', 85 inclusive, are inert or non-expansible and each section at its end is supported on a bushing 24.

The expanding section 25 consists of a sleeve divided longitudinally, into the sections 26 and 27, shown in Figs. 4 and 6.

Fig. 4 shows that the inner ends of the members 26 and 27, of the section 25, are provided with a groove 28 in which to receive a flange 29 extending laterally from the 95 thrust washer 30. The groove 28 is wider than the flange 29 of the washer 30, so as to permit some radial movement of the sections 26 and 27 at the same time the flange 29 in association with the groove 28 prevents 100 the sections 26 and 27 from falling away from the shaft 15. The sections 26 and 27 are provided with sectional heads 31 and 32, and these heads are bored with tapering 105 openings. In the head 31 the opening converges toward the axis inwardly, of the sec-

tion, while in the head 32 the opening converges in the same direction, but outwardly of the section.

Mounted on the shaft 15, and between the bushing 24 and the sleeve 23, is a corresponding tapered ring 33 in the shape of a truncated cone. A similar cone ring 34 is mounted at the end of the sleeve 23 under the sections 26 and 27 and these cones are separated by a sleeve 23. A reciprocating toggle head 35 is slidable on the shaft 15 and is positively driven by keys, 36-37, projecting from opposite sides of the shaft. The head 35 has some rotary lost motion 15 with respect to the shaft, as a result of the circumferentially extending slots 38 and 39 in which the keys 36 and 37 move when the shaft may be rotated to a limited extent without rotating the head.

20 A toggle heel 40, in the form of a sleeve, is slidable on the keys 41 and 42 on the shaft 15 and is positively rotated with the shaft, but is capable of axial adjustable movement thereon. Threaded on the end of the shaft 15 is a nut 43 for the purpose of adjustably moving the toggle heel along the shaft to adjust the toggle mechanism that operates the expandable members 26 and 27. Threaded on the shaft 15, and parallel with the nut 43, is a disk 44 that may be clamped to the nut 43 by a cap screw 45. When the nut 43, in the disk 44, has been rotated on the shaft 15 to a suitable point, the screw 45 is turned whereby the nut is firmly held on the shaft in adjusted position by the clamping effect of the disk 43, or the stress on the threads of the shaft exerted between the nut 43 and the disk 44.

On diametrically opposite sides of the heel 40 and in its transverse face are depressions 46 and corresponding depressions 47 are made in the face of the toggle head 35. These depressions are to receive ends of the toggle links 48 and 49. The head 32, of the sections 26 and 27, are perforated, as at 50, to receive driving pins 51, that are firmly secured in the confronting end of the head 35 and which serve as drivers for the sections 26 and 27. The perforations in the head 32 are sufficiently large to permit some radial movement of the sections 26 and 27 when they are expanded into larger than normal diameter.

55 The two-part ring 52 is provided with axially divided sections 53 and 54 which are located in a groove 55 made in the shaft 15, and are held in place by a one-piece ring 56 that is placed over the sections 53 and 54 and held in its place by the screws 57. This 60 structure serves as a stop for the movement of the head 35 towards the sections 26 and 27, in the operation of expanding the latter. It also serves as a stop to prevent excessive movement of the series of unexpandable sections 16 to 16¹, inclusive, and the distance

tube 23 and the bushing 24 along the shaft.

When the mandrel and its parts are in normal relaxed, or contracted position, the keys 36 and 37 are in the rear of the slots 38 and 39, as shown in dotted line positions 70 in Fig. 6. Now, if resistance be applied to the sections 26 and 27 of the expandable section of the mandrel, the shaft 15 will move ahead and with it the keys 36 and 37 until they strike the boundary shoulders in the slots 75 38 and 39. At the same time that the shaft moves ahead, the toggle heel 40 moves with it and the links 48 and 49 of the toggle are moved from their angular position shown in Fig. 9 to approximately the positions shown 80 in Fig. 8, thereby moving the toggle head 35 axially of the shaft, as shown in dotted lines in Fig. 8, causing the sections 26 and 27 to move upon the truncated cones 33 and 34 and separating the sections 26 and 27 to 85 a greater extent from each other increasing the diameter of the sections or expanding section 25 of the mandrel. The operation will move all of the sections 16-16¹, inclusive, along the shaft to a limited extent 90 determined by the washer 21 against the operation of the springs 22, so that when the shaft 15 is rotatably moved in an opposite direction, the springs 22 will return the parts to normal positions. In the operation 95 of expanding the mandrel section 25 the links 48 and 49 are never moved into parallelism with the true axial line of the shaft 15 because by the time they arrive at the position shown in Fig. 8, the end of the head 100 35 has contracted the abutment ring sections 53-54, which positively limit the movement of the toggle head.

When it is desirable to adjust the relative 105 positions of the head 35 and the heel 40, the screw 45 is loosened, which will permit the nut 43 to be readily rotated upon the threaded end of the shaft 15, and thereby the heel 40 is moved axially of the shaft the desired 110 distance, thereupon the screw 45 is tightened and the heel will be again held in adjusted place.

In making spiral pipe the section 25 is expanded forcibly into driving contact 115 with the inner surface of that portion of the pipe which has previously been formed upon the section 16, and it is the section 25 that is forcibly rotated with the shaft. The other sections 16 may be rotated with the shaft or may rotate freely thereon, there being no positive means by which they are 120 driven.

In the illustration above it is assumed that the shaft 15 is driven clockwise when looking at the end furtherest removed from the source of power or looking toward the end upon which the expanding instrumentalities are located.

Of course it will be manifest, to persons skilled in the art, that as many of the sec- 130

tions 16 may be employed as desired and that when required the section 25 alone may be used in some instances to perform its desirable function.

5 While I have herein shown a single embodiment of my invention for the purpose of clear disclosure it will be manifest that very many changes may be made in the general arrangement and configuration of the 10 parts within the scope of the appended claims.

Having described my invention what I claim as new and desire to secure by Letters Patent, is:—

15 1. An expandible mandrel comprising a rotatable shaft; a toggle heel rotatable with the shaft; a toggle head, spaced away from the heel, rotatable with the shaft after the toggle has been closed and axially movable 20 thereon during the closing operation; toggle links between the heel and the head arranged to move the latter axially when the shaft is rotated before the head is rotated; two separated mandrel members axially 25 movable by the toggle head and means to increase the diametric distance of separation of said members when so moved.

2. An expandible mandrel comprising an

expandible shell; a rotatable shaft therein; a toggle heel adjustably fixed to the shaft; 30 a toggle head, having a lost motion rotary engagement with the shaft; toggle links between the heel and head arranged to move the head axially of the shaft when the latter is rotated and before the shaft engages 35 the head in positive driving relation and means to diametrically expand said shell by the axial movement of said head.

3. An expandible mandrel comprising a shaft; a series of non-expandible sleeves or 40 sections removably mounted thereon; an expandible section, on said shaft; a yielding abutment on the said shaft at one end of said section; a rotatable toggle at the other end, one member thereof rotatable with the 45 shaft, the other member having rotary lost motion connection therewith; toggle links connecting said toggle members, movable by the relatively rotary displacement of said members and means for expanding the ex- 50 pansible section by operation of the aforesaid toggle.

In testimony whereof I hereunto subscribed my name.

CARL G. NAYLOR.
